UNITED STATES PATENT OFFICE.

JOHN MAILER, OF SAN FRANCISCO, CALIFORNIA.

BOILER-FURNACE.

SPECIFICATION forming part of Letters Patent No. 247,080, dated September 13, 1881.

Application filed June 4, 1881. (Model.)

To all whom it may concern:

Be it known that I, JOHN MAILER, of San Francisco, in the county of San Francisco and State of California, have invented a new and 5 useful Improvement in Boiler-Furnaces, of which the following is a specification.

This invention is designed as an improvement upon the boiler fire-box for which Letters Patent No. 227,278 were issued to me May 10 4, 1880; and its object is to still further assure the complete combustion of the fuel and gases in the fire-boxes of steam-boilers, evaporators, &c.

Figure 1 is a sectional front elevation on line 15 *xx* of Fig. 2, showing the application of my improved device to a pair of multitubular boilers. Fig. 2 is a sectional side elevation of the same on line *yy*, Fig. 1. Fig. 3 is an elevation of the inside of the fire-chamber door. 20 Fig. 4 is an enlarged front elevation, showing some of my perforated fire-bridge blocks.

Similar letters of reference indicate corresponding parts.

In the drawings, A A represent a pair of 25 stationary cylindrical boilers set in brick-work B. C represents the fire box or chamber; C', the ash-pit; D, the combustion-chamber on the opposite side of the bridge-wall from the fire-chamber C; and E is the bridge-wall, built up 30 from the bottom of the inclosing brick-work B to and about the boilers A A, so that none of the products of combustion from the fire-chamber C can pass between said bridge-wall E and boilers A A.

35 A short distance above the grate-bars F the bridge-wall E is provided with several rows of perforations, *aa*, extending from front to rear thereof, through which the smoke and gaseous products of combustion pass from fire-chamber C to combustion-chamber D. By the passage of these products of combustion through 40 the perforators *aa* the walls of the latter be-

come highly heated and radiate their heat upon the former, the temperature of which is thereby so increased that their complete combustion in the chamber D is assured when mingling with the air introduced through the perforated pipes G, laid in the supplementary bridge-walls H I in the said chamber D.

The perforated portion of the bridge-wall E 45 may be constructed of fire-brick laid with suitable spaces between them; or it may be built up with a mixture of fire-clay, salt, and sand, through which plugs of wood are inserted at suitable intervals, so that when a fire is built 50 in the fire-chamber C the plugs will burn out, while the wall becomes hardened, thereby leaving the suitable perforations *aa*.

The furnace or fire-chamber door M has its 55 front perforated, as shown at *c*, and its lining perforated, as shown at *d*, and screwed or otherwise secured in the perforations *d* are short tubes *f*, (about two inches long,) that project 60 inward toward the door-front. When there is a fire in the fire-chamber C these tubes *f* become 65 very hot therefrom and elevate the temperature of the air passing through the door M into said fire-chamber C, and said tubes *f*, being numerous and of thick metal, retain 70 heat, so that they do not become much reduced in temperature when the door M is opened for replenishing the fires.

Having thus fully described my invention, I claim as new and desire to secure by Letters Patent—

In a boiler-furnace, the perforated door M, provided with the air-tubes *f*, in combination with the bridge-wall having perforations *aa*, as shown and described.

JOHN MAILER.
